United States Patent Office

Des. 183,093

Patented June 24, 1958

183,093

HEAD BOARD

William T. Harris, Missoula, Mont.

Original application November 7, 1955, Serial No. 38,769.
Divided and this application May 21, 1957, Serial No.
46,265

Term of patent 7 years

(Cl. D5—4)

Fig. 1

This application is a division of my copending application D. 38,769 filed November 7, 1955.

I claim:

The ornamental design for a head board, as shown and described.
